UNITED STATES PATENT OFFICE.

EDMOND W. T. RICHMOND, OF ROMFORD, ENGLAND.

DESIGN FOR A GAS-STOVE.

SPECIFICATION forming part of Design No. 33,875, dated January 8, 1901.

Application filed December 11, 1900. Serial No. 39,555. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design consist of the body portion A, having the facets *a*; the wings B, projecting outwardly from the corners of the body portion and upwardly above it, and a laterally-projecting handle D,

arranged in line with the body A. The body portion and handle are ornamented, the former with arch-shaped figures *b*, containing fillets *c*, and with circular openings *d*, and the handle is ornamented with a series of parallel vertically-arranged grooves *f*.

I claim—

The design for a gas-stove, substantially as herein shown and described.

In testimony whereof I have hereunto subscribed my name.

EDMOND W. T. RICHMOND.
